UNITED STATES PATENT OFFICE.

GEORG POHL, OF MELVIN, IOWA.

DESIGN FOR A GARMENT-HANGER.

46,100.

Specification for Design.

Patented July 14, 1914.

Application filed May 15, 1914. Serial No. 838,879. Term of patent 7 years.

To all whom it may concern:

Be it known that I, GEORG POHL, a citizen of Tyrol, Austria-Hungary, residing at Melvin, in the county of Osceola and State of Iowa, have invented a new, original, and ornamental Design for Garment-Hangers, of which the following is a specification, reference being had to the accompanying drawing, forming part thereof.

The figure is a perspective view of a garment hanger, showing my new design.

I claim:

The ornamental design for a garment hanger, as shown.

GEORG POHL.
